UNITED STATES PATENT OFFICE.

ROBERT SANFORD RILEY, OF WORCESTER, MASSACHUSETTS, ASSIGNOR TO SANFORD RILEY STOKER CO., OF WORCESTER, MASSACHUSETTS, A CORPORATION OF MASSACHUSETTS.

STROKE ADJUSTER FOR AUXILIARY FUEL-FEEDING DEVICES.

Application filed December 24, 1919. Serial No. 347,088.

To all whom it may concern:

Be it known that I, ROBERT SANFORD RILEY, a citizen of the United States, residing at Worcester, in the county of Worcester and State of Massachusetts, have invented new and useful Stroke Adjusters for Auxiliary Fuel-Feeding Devices, of which the following is a specification.

This invention relates to a fuel feeding mechanism and particularly to that type in which the fuel is fed into the furnace by a reciprocating plunger which by its motion, gives a smaller degree of motion to an auxiliary means for further feeding the fuel toward the discharge point of the furnace.

The principal objects of the present invention are to provide an improved means for regulating the extent of movement of the auxiliary fuel feeding device; to provide regulating means which can be readily and easily adjusted by hand, and which will be so arranged with respect to the rest of the apparatus as to avoid any possibility of damage which might be caused in the old constructions by an inaccurate placing of the adjusting elements; to provide a simple means for holding the adjusting mechanism in proper adjusted position; to provide an adjusting means constructed on the principle of a curved block preferably having abrupt steps as stops to control the stroke of the auxiliary fuel feeding device; and to form the top of the adjuster so as to form an indicator to show the condition of the adjustment to which the device is set.

Further objects and advantages of the invention will appear hereinafter. Reference is to be had to the accompanying drawings, in which

Fig. 1 is a plan of a stoker of the type illustrated in my prior Patent No. 1,090,651, dated March 17, 1914, showing a preferred embodiment of this invention applied thereto;

Fig. 2 is a side view;

Fig. 3 is a side view on enlarged scale, and

Fig. 4 is a transverse sectional view on the line 4—4 of Fig. 3.

The invention is shown as applied to a type of self-feeding stoker which involves

a plurality of retorts all alike, each one having a stationary retort bottom 3 and longitudinally movable side walls 4. Air supplying outlet members 5 are mounted upon the upper edges of the walls 4 and move with them for the purpose and in the manner described in said patent. Also it will be understood that the fuel is fed from each hopper 8 by means of a reciprocating plunger 11. This plunger forces the fuel into the forward end of the retort and constitutes a primary fuel feeder. The side walls 4 and air supplying members 5 constitute auxiliary fuel feeding devices and are reciprocated with a reduced extent of motion by the primary feeder by connections comprising bars 15 having forwardly extending rods 17 each provided with a head 21. Two of these rods pass through opposite ends of a wrist pin 19 which extends through the plunger. Thus each plunger operates a side wall on each side thereof through a rod 17. This wrist pin 19 reciprocates positively of course, with the plunger as is the case in the above mentioned patent and also in my Patent No. 1,284,929, dated Nov. 12, 1918. The wrist pin positively moves the rod 17 back to a definite position on each outward stroke by engaging the head 21 and forces it inward throughout the last part of its operative stroke by transmitting its motion to the bar 15. The rest of the stroke constitutes lost motion as far as the side walls are concerned as is well understood.

According to my above mentioned patent of Nov. 12, 1918, removable blocks or fillers were placed on the rod 17 to regulate the amount of motion of the side walls 4. One of the objects of this invention is to avoid the use of removable members which may be displaced in one way or another or lost and to provide a device which will always be in place ready to be adjusted to the proper position to secure the necessary amount of motion of the side walls and air supplying outlet members.

For this purpose, I mount the end of a spring 22 in a casting 18 or the like on the head 21 of each rod 17. This spring is shown as having a horizontal portion se-

cured in position by a screw 20 and as provided with a coil at 23 and a downwardly extending U-shaped portion. The extreme end of this U-shaped portion extends into 5 an adjuster block 25 which is supported by this spring. The resiliency of the spring is such and its shape is so designed that it will normally tend to hold this block inwardly toward the retort and up in the position 10 shown in Fig. 3. In that position the bottom or widest part of the adjuster contacts with the end of the bar 15 and consequently a maximum extent of motion is given to the auxiliary fuel feeding device, 15 on each stroke of the plunger. The wrist pin engages the adjuster at its widest portion near the end of each stroke and moves it a distance corresponding to the thickness of the adjuster at that point.

20 The adjuster is made of different widths above and I prefer to accomplish this by means of steps 26 so as to get a plurality of definite motions of the auxiliary fuel feeding device. It will be seen therefore that 25 the adjuster block 25 can be lowered one step, or two steps if desired, as shown in Fig. 2 and thus there will be a narrower part of the adjuster between the wrist pin and the bar 15. Consequently, the extent of 30 motion of this bar will be reduced accordingly.

This adjuster has a handle 27 integral with it as shown and extending from it at a definite angle so that when the adjuster is in its 35 lowermost position, as indicated in Fig. 2, this handle will be horizontal and will extend just above the tops of the associated parts. It is to be understood that there are two of these for each plunger and there are 40 several plungers across the stoker and these several handles will indicate whether all of the adjusters are in the same position. They also indicate when they are all in lowermost position, namely, that in which the side 45 walls have the smallest motion. The adjuster 25 has a projection 28 at the bottom coming up under a shoulder 29 of the casting and limiting the upward motion of the adjuster to the position shown in Fig. 3.

50 In operation, assuming that the parts are in the position shown in Fig. 3, if it is found that the auxiliary feeding device had too great an extent of motion, this may be reduced for each individual side wall by 55 simply grasping the several handles 27 one after another and forcing the adjusters down against the resistance of the springs 22. It can be done also simply by delivering a blow downwardly on each handle. This 60 is done, of course, when the wrist pin is a sufficient distance away from the adjuster.

It will be observed that the spring not only forces the adjuster up, but forces it toward the grate bars so that the mere 65 pushing down of the handle far enough to

drop the next step 26 below the edge of the bar 15 will automatically result in the forward motion of the adjuster to project that next step under the end of the plunger and prevent its rising until pulled back and replaced by the operator. When moved up the abrupt edge of each step will serve as a stop by coming against the bottom of the bar 15. 70

It will be seen therefore that in operation each side bar 15 controls the movement of 75 its corresponding side rod as in the case of my above mentioned patent of Nov. 12, 1918 and that the side bar withdraws the side rod to the same position on each return stroke independently of the features of this 80 invention. But the travel toward the bridge wall is varied by changing the amount of lost motion by the extremely simple adjustment of the stroke above described.

This adjuster is so constructed that it can 85 not get out of place. All danger of misplacing it, which has been present in former constructions, is done away with and it is always in position ready to be adjusted in accordance with the will of the operator. 90 Furthermore, the top of the adjuster is so shaped that it can be seen at a glance whether all the adjusters are in the same position and whether that position is the right one. 95

I am aware of the fact that modifications can be made in this invention and that it can be applied to other types of stokers or fuel feeding machines than the one illustrated herein without departing from the 100 scope of the invention as expressed in the claims.

Therefore I do not wish to be limited in these respects, but what I do claim is:—

1. The combination with a plunger for 105 feeding fuel or the like, an auxiliary feeding device, and a lost motion connection between them for transmitting part of the motion of the plunger to the auxiliary feeding device, of an adjuster having portions differing in width in the direction of the length of the stroke of the plunger arranged in the form of steps, and means connected with the adjuster tending to move it so as to bring its widest portion into operative position for supporting it in its adjusted positions, said adjuster being movable transversely into different positions in the path of the lost motion connection with the edge of a step limiting its movement in the 110 direction in which said means tends to move it, so that its portions of different width will vary the effective length of said motion. 115

2. In a stroke adjuster for an auxiliary fuel feeding device, the combination with a 125 main fuel feeding device having a plunger for feeding fuel provided with a wrist pin thereon and an auxiliary fuel feeding device having a bar connected with it for moving it, of a block having a series of portions of 130

different widths arranged in the form of steps adapted to be placed between the plunger wrist pin of the main fuel feeding device and the end of the bar connected with 5 the auxiliary fuel feeding device to vary the stroke thereof, the ends of said steps serving as stops by coming against the bar, said block being movable transversely with respect to the stroke of the wrist pin to bring the different portions into operation, and a 10 spring for holding the edges of the steps against the bar.

In testimony whereof I have hereunto affixed my signature.

ROBERT SANFORD RILEY.
